UNITED STATES PATENT OFFICE.

NATHAN FLEGENHEIMER, OF PHILADELPHIA, PENNSYLVANIA

DISPLAY LID FOR CONTAINERS

Application filed December 7, 1927. Serial No. 238 393

This invention relates to new and useful improvements in container lids and aims to provide a lid of either the wedge or slip type and of any particular shape that is constructed to include at its center a plate or disk of transparent material whereby the container's contents may be viewed by the purchasing public with the obvious result of bringing about a more ready sale thereof.

In carrying out the invention there is provided generally, a rigid edging of metal or other material and a central portion of transparent material, the edging being so constructed as to permit of the wedging of the lid within the container, or the disposition of the same over the open end of the container.

In the drawings wherein there is disclosed several embodiments of the present invention:

Figure 1 is a fragmentary upper end perspective of a circular container within which is arranged one form of the lid constructed in accordance with the present invention.

Figure 2 is a detail horizontal section therethrough.

Figure 3 is a slightly modified form of the wedge design of lid.

Figure 4 is a fragmentary horizontal section therethrough.

Figure 5 is a plan view of a still further modification.

Figure 6 is a fragmentary horizontal view thereof.

Figure 7 is a plan view of a still further modification.

Figure 8 is a fragmentary horizontal section taken through Figure 7.

Figure 9 is a fragmentary perspective of the upper open end of a can over which is disposed a slip type of lid constructed in accordance with the present invention.

Figure 10 is a detail horizontal section thereof.

Figure 11 is a top plan view of a still further modified form of the wedge type of lid, and

Figure 12 is a fragmentary horizontal section therethrough.

In Figures 1 and 2 A designates fragmentarily a cylindrical container formed or constructed at its upper end with an inwardly extending flange a . This type of container is well known and a more detailed description thereof is not believed necessary.

Containers of this character are usually provided with metallic wedge type of lids that are adapted to be wedged within the flange. In the present instance the lid constructed in accordance with the present invention and disclosed in Figures 1 and 2 consists of a relatively wide ring 5 formed at its lower edge with an inwardly extending flange 6 of predetermined width. The upper edge of the ring is formed with a narrow outwardly extending flange 7 that is beaded at its outer edge as at 8. The bead of this flange adapted for engagement upon the flange a of the container A when the said ring 5 of this type of lid is wedged within the container flange A. Arranged upon the inner face of the lid flange 6 is a ring 9 of cardboard, paper, or other suitable material upon the face of which is printed any suitable advertising indicia as disclosed in Figure 1.

Disposed within the ring 5 and resting upon the cardboard or paper ring 9 is a disk 10 of plate glass, isinglass, or other suitable transparent material. After this disk of transparent material 10 has been disposed within the ring 5 a steel wire ring 11 is wedged within the lid ring and into close engagement with the glass disk 10. The flange 6 of the lid ring 5 is formed at spaced predetermined points with struck out tongues 12 that are bent upwardly alongside of the inner face of the ring 5 prior to the disposition of the ring 9, transparent disk 10 and ring 11 within the ring of the lid. After the wire ring 11 has been disposed in position, the upper end of these tongues 12 are bent over into engagement with the ring 11 as clearly indicated in both Figures 1 and 2.

Obviously if not desired, the advertisement carrying ring 9 may be dispensed with.

The forms of the invention disclosed in Figures 3, 4, 5, 6, 11, and 12, are quite similar to the form of the invention disclosed in Figures 1 and 2 and previously described. However in the form of construction disclosed in Figures 3 and 4 the lid ring 5^a is formed adjacent its upper edge with short struck out lugs or tongues 17^a that are bent inwardly into horizontal engagement above the steel wire ring 11^a.

In the form of the invention disclosed in Figures 5 and 6 the inner edge of the lower ring flange 6^b is formed at predetermined spaced points with relatively elongated strips of the material forming the lid edging, said strips providing tongues 17^b that are bent inwardly over the inner face of the flange 6^b and thence upwardly as more clearly indicated.

ed in Figure 6. After the disposition of the steel wire ring 11^b the upper ends of these tongues are turned over into engagement with the ring for securely locking the same in engagement with the transparent disk 10^b.

In the form of the invention disclosed in Figures 7 and 8 there is welded or soldered to the inner face of the lid ring 5^c and at the lower edge thereof relatively short strips of metal to provide tongues 17, these strips of metal being secured to the lid ring only at their lower ends so that after the steel wire rings 11^c are disposed in position in engagement with the transparent disk 10^c the upper ends of these tongues may be bent over into engagement with the ring 11^c for securing the same in position.

In the form disclosed in Figures 11 and 12 the transparent disk retaining wire ring 17^d is soldered to the lid ring 5^d at predetermined small points throughout the circumference thereof. These points of connection are designated 17^d. Obviously the ring 11^d is not soldered to the lid ring until after the transparent 10^d has been disposed in position.

In the form of the invention disclosed in Figures 9 and 10 there is provided a slip type of lid, the same consisting of a relatively large ring or band 20 of sheet metal constructed for disposition over the open upper end of a container B. The upper edge of this ring or band is formed with an inwardly extending flange 21, while arranged within

said flange and soldered and welded in position therein is a structure designated generally by the reference character 21 similar to any type of the wedge form of lid indicated in the other figures of the drawings.

It will thus be seen that I have provided several highly novel, simple and useful forms of display lids for containers each of which is well adapted for the purposes designated, even though I have herein shown and described the invention in various forms as consisting of certain detail structural elements, it is nevertheless to be understood that some changes may be made therein without affecting the spirit and scope of the appended claim.

Having thus described the invention, what I claim as new and desire to secure by Letters Patent is:—

In a container lid of the character described, a rim, a disk of transparent material arranged within the rim, means associated with said rim for supporting the transparent material therein, means for rigidly securing the transparent material within said rim, said means consisting of a wire ring snugly arranged within said rim, and projections on the rim adapted to be bent over the said wire ring for securing the same snugly against the transparent material.

In testimony whereof I affix my signature.

NATHAN FLEGENHEIMER.
